SAMUEL W. SHOREY, OF GALESBURG, ILLINOIS.

Letters Patent No. 97,558, dated December 7, 1869.

BOOT-CONFORMATOR.

The Schedule referred to in these Letters Patent and making part of the same.

To all whom it may concern:

Be it known that I, SAMUEL W. SHOREY, of Galesburg, in the county of Knox, and State of Illinois, have invented a new and useful improvement in instruments for taking the measure and shape of the human foot, and which I denominate a Boot-Conformator; and I do hereby declare that the following is a full, clear, and exact description of the same, reference being had to the accompanying drawing, forming part of this specification, and in which—

Figure 1 represents a plan of a boot-conformator constructed in accordance with my invention;

Figure 2, a longitudinal sectional elevation of the same; and

Figure 3, an inverted plan of the hinged or rising-and-falling-frame portion of the instrument, with its measuring-attachments and sole-plate.

My invention consists in an instrument or device for taking not only the measure but the shape of the foot in a positive manner, as contradistinguished from merely draughting the contour of the same, and in such a way as that it gives the exact tread or contour when the foot is in its natural position, as raised from the ground, or before it is spread out and changed by pressure on the ground, said instrument operating to measure the foot every time alike, so that, by means of it, a last can be fitted up by the boot-maker, or made to order by the last-maker, so as to correspond with the foot exactly, however varied the shape of the foot may be, either as a whole, or at certain parts.

Thus said instrument is, or may be constructed to take, in addition to the general measure of the foot, the height of the instep, also of the ball and great toe, the arch of the foot, and, in fact, all, or different irregularities.

Referring to the accompanying drawing—

A represents a sole-plate, which is carried by a surrounding frame, B, made up, in part, of variously-disposed or radiating base-bars, F, and which is so hung, or connected with a main base-board, G, that rests upon the ground, as that said frame is free to rise and fall, for which purpose it may be hinged at its one end, as at a, and suitably guided or directed at its other end, as at b.

Arranged on the radiating bars F, by means of strap-like attachments, so as to be capable of being slid along the same, preferably under slight frictional hold, by springs e, are adjustable measuring-uprights C, which are each drawn inward by independent springs s, for the purpose of insuring a soft or easy pressure of said uprights against different portions of the foot as it rests upon the sole-plate A.

These uprights C serve to give the tread or contour of the foot while the latter is in a raised position, and retains its natural shape, inasmuch as the foot is only made to rest freely, without weight or pressure, on the sole-plate, or the latter moved up to the foot when raised, and then the frame B brought down, so as to cause knives or markers E,

attached to the lower ends of the uprights C, to indicate, on a sheet of paper, or other material, placed on the base-board G, the different positions assumed by the uprights C in their bearing against the foot, which gives the tread or contour of the latter.

Grooves, m, should be made in the base-board G, to prevent the markers from being dulled by contact with said board, and to insure their proper action.

To measure the height of the foot at different parts—as, for instance, the height of the instep, also of the ball and great toe, or other irregularities—certain of these adjustable measuring-uprights C are provided with vertically-adjustable horizontal bars D, arranged so as to be capable of being slid up or down said uprights, and accordingly as they bear or come in contact with the portions of the foot they are designed to get the height of, the measurement thus attained being recorded by scales, d, on the uprights, up or down which said horizontal bars are adjusted.

These vertically-adjustable horizontal bars D may be changed, as required, to fit corresponding uprights C on opposite sides of the frame, to suit right and left measurements, or for other reasons.

The arch of the foot and other under measurements—as, for instance, the under side of the great toe, which is in some feet much more raised than in others—may be taken by sight directed across the frame, under the foot, and, as in the measurements by the scales d, be noted down, for use in connection with the marks made to indicate the tread or contour, as hereinbefore described.

What is here claimed, and desired to be secured by Letters Patent, is—

1. The combination of the sole-plate A, outside surrounding frame B, and radial bars F, with the adjustable measuring-uprights C and springs s, for measuring the tread or contour of the foot, substantially as specified.

2. The combination, with the adjustable measuring-uprights C, or certain of them, of the vertically-adjustable horizontal bars D, for measuring the height of the foot at certain parts, as well as its contour or tread, essentially as herein set forth.

3. The combination of the springs s with the adjustable measuring-uprights C, operating independently of each other, substantially as and for the purpose specified.

4. The arrangement of a scale or scales on the measuring-uprights C, which carry the vertically-adjustable horizontal bars D, essentially as described.

5. A boot-conformator made up of a sole-plate, A, surrounding hinged or vertically-operating frame B, yielding or adjustable measuring-uprights C, with their markers E and vertically-adjustable horizontal bars D, substantially as specified.
